L. J. BLACK

HYDRAULIC SWIVEL

Filed Aug. 19, 1922

Fig. 1.

Attorney.

UNITED STATES PATENT OFFICE.

LEE J. BLACK, OF BEAUMONT, TEXAS.

HYDRAULIC SWIVEL.

Application filed August 19, 1922. Serial No. 582,849.

To all whom it may concern:

Be it known that I, LEE J. BLACK, a citizen of the United States, residing at Beaumont, in the county of Jefferson and State of Texas, have invented certain new and useful Improvements in Hydraulic Swivels, of which the following is a specification.

This invention relates to hydraulic swivels used with rotary well-drilling machinery for making a water-supply connection with the drill stem.

The present device is an improvement over the one disclosed in Patent No. 1,408,975, dated March 7, 1922, and the object of the invention is to provide a novel and improved combination and arrangement of elements which permits perfect lubrication of the swivel stem.

In order that the invention may be better understood, reference is had to the accompanying drawing, wherein:

Figure 1 is a side elevation of the improved structure, partly in section, and Fig. 2 is an elevation viewed from another side.

Referring specifically to the drawing, 5 denotes a swivel stem which passes through and is supported by the swivel cross-head 6, which latter is carried, as usual by a bail 7 to which the draw cable (not shown) is connected. The drawing shows only a fragment of the cross-head as its structure is immaterial to the present invention.

As in the patent hereinbefore referred to there is secured to the cross-head 6, by being screwed thereinto, the base ring 8 of a water-head 9, the latter being connected to the base ring by integral webs 10.

The water-head 9 is made hollow to form an oil reservoir 11, and it also has a central vertical opening to seat a stuffing box and a coupling device for the goose-neck 12 to which the water-supply hose is connected, and which delivers water to the stem 5. The stuffing box is shown at 13, and it extends downwardly from a base 14 which is threaded to screw into a bottom opening in the water-head. Inside the water-head, the base 14 has a hollow upward extension 15 which passes centrally through the reservoir 11 and through a top opening in the water-head to project therefrom for a short distance. The projecting end of the extension 15 is externally threaded to receive a

lock nut 16 which is screwed down against the top of the water-head.

The upper end of the swivel stem 5 passes into the stuffing box 13, and the latter is provided with a screw cap 17 for holding a gland or follower 18 and a packing 19. The stuffing box interior is continued through the base 14 and also partly into the extension 15, and in the side of the latter, where it is joined to the base, are oil ducts 20 leading, 65 with a downward inclination, from the oil reservoir 11 to the interior of that portion of the stuffing box containing the packing 19 which surrounds the swivel stem 5.

It will be evident from the foregoing that 70 the oil in the reservoir 11 passes by the way of the ducts 20 to the packing space of the stuffing box 13, and this oil seeps through and is absorbed by the packing 19 around the upper end of the swivel stem, so that 75 the latter is kept lubricated at all times, which is of the utmost importance in structures of this kind. The water-head has a top filler opening 21 leading to the oil reservoir and closed by a screw plug 22, and 80 also a bottom clean-out opening 23 closed by a screw plug 24.

The goose-neck 12 is connected to the upper end of the extension 15 by being screwed thereinto, said extension therefore 85 also serving as a coupling means for the goose-neck.

I claim:

1. In a hydraulic swivel, a hollow water-head forming an oil reservoir, a stuffing box carried by said head and provided in the wall of its packing space with oil ports to permit saturation of the packing in said space, and a swivel stem extending into said stuffing box and in wiping contact with said packing.

2. In a hydraulic swivel, a swivel stem, a hollow water-head, and a stuffing box on the bottom of the water head and having an upward extension through the interior of the 100 water-head, the swivel stem passing into the stuffing box, and the interior of the water-head forming an oil reservoir, the aforesaid stuffing box extension having oil ducts leading from the oil reservoir to the packing 105 space of the stuffing box.

3. In a hydraulic swivel, a swivel stem, a hollow water-head, a stuffing box on the bottom of the water-head and having a hollow upward extension through the interior of the 110

water-head, the swivel stem passing into the stuffing box, and the interior of the water-head forming an oil reservoir, the aforesaid stuffing box extension having oil ducts leading from the oil reservoir to the packing space of the stuffing box, and a water-supply connection on the upper end of the stuffing box extension and opening into the interior thereof.

10 4. In a hydraulic swivel, a hollow water-head having top and bottom openings, a stuffing box having a base which is secured in the bottom opening, and a hollow extension projecting upwardly from the base through the interior of the water-head, said extension passing through the top opening of the water-head, a lock nut carried by the upper end of the extension and engaging the top of the water-head, and a swivel stem passing into the stuffing box, the interior of the water-head forming an oil reservoir and the aforesaid stuffing box extension having oil

ducts leading from the reservoir to the packing space of the stuffing box.

5. In a hydraulic swivel, a hollow water-head having top and bottom openings, a stuffing box having a base which is secured in the bottom opening, and a hollow extension projecting upwardly from the base through the exterior of the water-head, said extension passing through the top opening of the water-head, a lock nut carried by the upper end of the extension and engaging the top of the water-head, a swivel stem passing into the stuffing box, the interior of the water-head forming an oil reservoir and the aforesaid stuffing box extension having oil ducts leading from the reservoir to the packing space of the stuffing box, and a water-supply connection on the upper end of the stuffing box extension and opening into the interior thereof.

In testimony whereof I affix my signature.
LEE J. BLACK.
